UNITED STATES PATENT OFFICE

FLETCHER H. FIELD, OF DETROIT, MICHIGAN, ASSIGNOR TO RHODES METALLIC PACKING COMPANY, OF DETROIT, MICHIGAN, A CORPORATION OF MICHIGAN

METHOD OF FORMING PACKING

Application filed November 3, 1930. Serial No. 493,203.

This invention relates to a method of forming metallic packing such as is used in packing stuffing boxes about working shafts, rods and the like.

5 My invention constitutes an improved modification of the process described in United States Letters Patent No. 1,629,051 dated May 17, 1927.

10 My invention has as its primary object to provide a commercially practical method of producing metallic packing formed of a plurality of sections or segments.

15 My invention contemplates a method or process resembling that described in the aforementioned Letters Patent wherein a plurality of flexible strips are led through forming means whereby the strips are interfolded and compacted and finally compressed in interlocked position, but modified to the extent that during the interfolding and compacting operation the strips are separated or divided into sections which when the packing is finally completed form a plurality of 20 interfitting or interengaging segments or sections.

25 One form of mechanism by means of which my improved method may be carried out or executed, is shown in the accompanying drawing, wherein

30 Figure 1 is a semi-diagrammatic plan view of the apparatus employed in carrying out my invention;

35 Figure 2 is a view partly in vertical section and partly in elevation of the structure illustrated in Figure 1;

Figure 3 is a transverse sectional view through the finished packing;

40 Figure 4 is a transverse sectional view taken substantially on the plane indicated by line 4-4 in Figure 2, and

Figure 5 is a view taken substantially on the plane indicated by line 5-5 in Figure 2.

45 In Figure 3 there is illustrated in cross-section one form of packing which may be produced in accordance with this invention and from an examination of this figure it will be apparent that the packing comprises a substantially square cross-section formed of a plurality of substantially triangular segments 10 which interfit to produce a pack-

ing substantially square in cross-section. Each of the segmental or triangular sections 10 is formed of a plurality of flexible strips of metal such as lead, babbitt, or any other preferred or desired material, these strips 55 being interfolded and constricted and compacted and finally compressed. The flexible strips may be coated with graphite or oil or both and the packing may be provided with a covering 11 of fabric or any other preferred or desired material.

In the form of packing illustrated in Figure 3, I have shown each section or segment 10 as being provided with a substantially centrally arranged core 12 which may be of any 65 desired material but preferably a material which is at least partly resilient or compressible.

By providing a packing composed of substantially triangular sections or segments, 70 either pair of opposed sections may be forced outwardly in opposite directions when the other pair of opposed sections are compressed. This increases the range of expansibility of the packing and thus increases its 75 efficiency.

In Figure 2 there is illustrated one form of apparatus by means of which my improved method may be practiced. As will be noted I provide a plurality of reels or spools 13, 80 each containing a strip of metallic ribbon 14. These spools or reels are mounted upon a platform or base 15. These metallic ribbons are led up through forming means consisting of an outer former 16 and an inner 85 former 17, these formers cooperating to produce an annular space which progressively decreases in size from the bottom to the top thereof, the upper adjacent edges of the outer and inner formers together forming a throat 90 18.

The space between the former 16 and former 17 is separated or divided into a plurality of sections, herein shown as four, by radially arranged division plates 19. This 95 produces four separate forming spaces 20 as will be apparent. Thus the metallic strips as they are led upwardly through the forming means are separated or divided into four sections and these division plates 19 prevent 100

the strips of adjacent sections from becoming interfolded or interlocked with the strips of the next adjacent section so that the packing when finally completed comprises a plurality of individual, separate but interfitting sections.

The reference character 21 indicates cooperating pairs of rolls which draw the metal strips upwardly, these rolls acting also to compact the interfolded strips and to finally shape the assembled sections into the desired exterior cross-section. If a packing of substantially square cross-section is to be produced, the profile of the rolls 21 will be substantially right-angular or V-shaped.

The metallic strips as they are drawn upwardly through the forming means are gradually drawn together or constricted and also longitudinally distorted and folded due to the progressively decreasing space between the formers 16 and 17 which act to exert a progressively increasing pressure upon opposed sides of the strips. This interfolding or constricting of the strips is practically completed as the strips emerge from the throat 18 of the forming means and the rolls 21 then compact and finally shape the packing. The manner in which the strips are interfolded and compacted together is semi-diagrammatically illustrated and may be seen by comparison of Figures 4 and 5.

Obviously, it may be and often times is desirable to associate a core or the like with the packing or with the sections thereof and in the drawing I have illustrated the core members 12 as being lead upwardly with the metallic strips 14 so as these strips are interfolded and compressed they will be interfolded and compressed around the cores. Thus the structure as illustrated in Figure 3 can be produced. If desired, but a single core member may be employed and this may be lead upwardly centrally or axially of the forming means and in the completed packing would be arranged at the juncture of the apices of the triangular sections.

While the rolls 21 serve to finally compress the strips of metallic ribbon into compact relation and to thoroughly interlock each strip with the adjacent strips so that they will not be readily torn apart, nevertheless by reason of the initial separation of the strips into several sections the action of these rolls will not be such as to interlock the strips of adjacent sections.

In addition to the inherent resiliency of each of the packing sections a packing constructed of substantially triangular sections as herein described has the added advantage, as mentioned hereinbefore, of the possibility of relative movement between the pairs of opposed packing sections.

Reservation is made to make such changes in any of the non-essential steps of the herein

described method as may come within the purview of the accompanying claims.

What I claim as my invention is:

1. In the method of forming a flexible packing having a plurality of substantially triangular sections, those steps which consist in leading a plurality of flexible strips from spaced sources of supply through forming means arranged to separate said strips into sections and to simultaneously apply progressively increasing pressure upon opposed sides of the strips of each section to interfold and compact said strips with each other, and then pressing and shaping the sections so that together they assume the desired exterior configuration. 80

2. The method of forming a multi-segment flexible packing which consists in leading a plurality of flexible strips from spaced sources of supply between formers arranged to apply progressively increasing pressure upon opposed sides of said strips to interfold and compact said strips with each other, simultaneously dividing the strips into a plurality of groups whereby the strips of each group form a separate segment, and then pressing and shaping the assembled segments into the desired cross-sectional configuration. 90

3. Those steps in the method of forming a sectional flexible packing which consist in simultaneously forming a plurality of sections of the packing, each section comprising a plurality of flexible strips of material interlocked with each other, feeding said sections into juxtaposition with each other, and compressing all of said sections to shape the assembled sections into the desired cross sectional configuration. 95

4. Those steps in the method of forming a multi-section flexible packing which consist in leading a plurality of flexible strips from spaced sources of supply through passages of progressively decreasing diameter to apply a progressively increasing pressure upon opposed sides of said strips to interfold and compact said strips with each other, leading the interfolded strips from said passages into juxtaposition to each other, and compressing the interfolded strips from all of the passages to shape the same into a packing strip having the desired cross sectional configuration. 115

5. Those steps in the method of forming a flexible packing having a plurality of sections movable relative to each other, which consist in dividing a plurality of flexible strips into groups, leading each group of strips through a passage of progressively decreasing cross section to apply progressively increasing pressure upon opposed sides of the strips of each group to interfold and compact the strips of each group with each other, discharging the strips from each passage into juxtaposition to the strips from the other passages, and simultaneously pressing and shaping the groups discharged from the sev- 120
125
130

eral passages to assemble the same in a strip having a predetermined desired cross sectional configuration.

6. In a method of the character described, those steps which consist in feeding a plurality of cores longitudinally and simultaneously forming an envelope for each core by leading a plurality of flexible strips from spaced sources of supply into contact with each core while applying pressure against both the inner and outer surfaces of each envelope as it is being formed to interfold said strips with each other and thereby compact and constrict said envelopes about said cores, and finally compressing and shaping the several assemblages into a desired cross sectional shape.

In testimony whereof I affix my signature.
FLETCHER H. FIELD.
